US00D333990S

United States Patent [19]

Johnson et al.

[11] Patent Number: Des. 333,990
[45] Date of Patent: ** Mar. 16, 1993

[54] METAL DETECTOR

[75] Inventors: **Gerald L. Johnson, Garland; Robert J. Podhrasky, Dallas, both of Tex.**

[73] Assignee: **Garrett Electronics, Inc., Garland, Tex.**

[**] Term: **14 Years**

[21] Appl. No.: **541,294**

[22] Filed: **Jun. 20, 1990**

[52] U.S. Cl. **D10/46**

[58] Field of Search **D10/46; 324/329, 327; 340/572**

[57] CLAIM

The ornamental design for a metal detector, as shown and described.

DESCRIPTION

FIG. 1 is a perspective view of a metal detector showing our new design, the broken line showing of the probe head and adjoining support armature is environmental only and forms no part of the claimed design; FIG. 2 is a perspective view, shown in an alternate condition of use;

FIG. 3 is a top plan view;

FIG. 4 is a bottom plan view;

FIG. 5 is a right side elevational view;

FIG. 6 is a left side elevational view;

FIG. 7 is a rear elevational view;

FIG. 8 is a front elevational view; and,

FIG. 9 is an enlarged detail view of the control panel of FIG. 1 thereof.

FIGS. 1 and 2 have been drawn on a reduced scale with respect to FIGS. 3-9.

FIG. 3

FIG. 4

FIG. 6

FIG. 8

FIG. 7

FIG. 9
